Primary Examiner — Mary Ann Calabrese*Assistant Examiner* — Catherine Ho(74) *Attorney, Agent, or Firm* — Demian K. Jackson; Jackson IPG PLLC(57) **CLAIM**

The ornamental design for a ticket dispenser, as shown and described.

DESCRIPTION

FIG. 1 is a perspective view of a ticket dispenser, showing our new design;

FIG. 2 is a front view of the ticket dispenser shown in FIG. 1;

FIG. 3 is a rear view of the ticket dispenser shown in FIG. 1;

FIG. 4 is a left view of the ticket dispenser shown in FIG. 1;

FIG. 5 is a right side view of the ticket dispenser shown in FIG. 1;

FIG. 6 is a top view of the ticket dispenser shown in FIG. 1; and,

FIG. 7 is a bottom view of the ticket dispenser shown in FIG. 1.

The broken line portion of the figure drawings is included to show portions of the article that forms no part of the claimed design.

1 Claim, 7 Drawing Sheets(56)
